VAPOR ELECTRIC DEVICE

William E. Pakala, Forest Hills, Pa., assignor to
 Westinghouse Electric Corporation, East Pitts-
 burgh, Pa., a corporation of Pennsylvania

Application August 11, 1942, Serial No. 454,372

10 Claims. (Cl. 315—166)

1

My invention relates to a vapor-electric device and particularly to an excitation system for improving the operating characteristics of a vapor-arc valve device.

In the operation of vapor-arc valve devices, two types of excitation have heretofore been utilized. The first, and for many years, the standard excitation system, has been a system maintaining a substantially constant, continuous excitation of a value sufficient to secure pickup of the arc to any positive anode. Usually the actual time of pickup was controlled by means of a suitable shield and grid system. The second method of excitation is the recently invented make-alive type in which the cathode spot is not maintained but reinitiated at the beginning of each conducting half cycle.

With the first method of excitation, it was necessary to maintain a heavy protective grid system in order to reduce the probabilities of arc back during the inverse half cycle. This heavy grid system resulted in excessive arc drop losses in the valve device. When the make-alive system is utilized, the shielding could be reduced to a minimum but the requirements of striking the cathode spot and producing the necessary vapor to insure pickup required excessive impulse energy.

In the excitation system according to my invention, a continuous excitation current is provided of sufficient intensity to maintain a cathode spot, but of too low intensity to maintain ionization sufficient to produce pickup, and a periodic current impulse is superimposed on the continuous excitation to produce the necessary ionization to secure pickup at the beginning of each conducting half-cycle.

It is accordingly an object of my invention to provide an excitation circuit having improved operating characteristics.

It is a further object of my invention to provide an exciting system requiring the minimum of excitation energy to secure reliable operation.

It is a further object of my invention to provide a direct-current excitation system having an alternating-current impulse superimposed thereon.

Other objects and advantages of my invention will be apparent from the following detailed description taken in conjunction with the accompanying drawing, in which:

Figure 1 is a schematic illustration of a vapor-

electric system according to my invention.

Figs. 2, 3 and 4 are graphical illustrations of

the component currents and resulting excitation current secured by my excitation system.

In the illustrative embodiment of my invention, an alternating-current circuit 10 is connected to a direct-current circuit 11 by means of a suitable transformer means 12 and the flow of current through the transformer 12 is controlled by means of a plurality of vapor-electric valves 13. Each of the vapor-electric valves 13 comprises a main anode 14 and cathode 15 within an evacuated container 16. The anode 14 is preferably surrounded by a suitable shield 17. Also each valve 13 is provided with a starting electrode 20 herein illustrated as of the high resistant make-alive type and a suitable keep-alive electrode 21. The starting electrode 20 and the keep-alive electrode 21 are preferably connected in parallel to a suitable source of continuous exciting current herein shown as a full wave rectifier 22 fed from a suitable alternating-current source such as the alternating current line 10.

While any suitable number of valves 13 may be utilized, I have herein shown a pair of alternately conducting valves 13, while it is apparent that any number of pairs of valves 13 may be utilized each pair having a similar excitation system. In order to divide the direct-current between the pairs of exciting electrodes 21, a high reactance 23, preferably of the coil type, is inserted between the pair of exciting electrodes 21, the positive side of the direct-current source 22 being connected to a mid tap 24 of the reactor 23 the other side of the direct-current source 22 being connected to the cathodes 15 of the valves 13. In order to secure a periodic alternating current impulse, I have provided a wave distorting impulsive system herein shown as of the reactor type, while it is obvious that any suitable impulsive device may be utilized. The preferred wave distorting system comprises a source 25 of alternating current having a capacitor 26 connected across its terminals and a suitable impedance 27 for controlling the flow of current from the alternating-current source 25 to the capacitor 26. A voltage sensitive variable reactor 28 is inserted between the alternating-current source 25 including the capacitor 26 and the excitation electrodes, 20 and 21 to control the flow of current from the source 25 to the electrodes 20 and 21. This voltage sensitive impedance 28 is usually in the form of a saturable reactor which, at low voltages, offers a very high impedance to the flow of current, but when saturating potential is supplied a sat-

urating current flows in the reactor and reduces its impedance to a very low value. At this time, a current impulse will flow from the alternating-current source 25 including the capacitor 26 to provide a short impulse 41 of high amplitude to properly ionize the container space at the beginning of the conducting half-cycle. The direct current flows to the reactor 23 and is substantially evenly divided between the two electrodes 21, or if the circuit interrupters 35 are closed between the starting electrodes 20, and returns through the cathode connection to direct-current source 22. Then at the instant that the top end of the secondary winding of transformer 25 is positive, a positive impulse flows through saturable reactor 28 to the exciting electrode 21, and if circuit interrupter 35 is closed, to starting electrode 20 of the left-hand valve 13. At the same instant, a negative impulse would be impressed on right-hand valve 13. Unless the negative impulse is bypassed it attempts to flow through the electrodes 20-21 of the right-hand valve 13, and reduces the total current to such a value as to interrupt current flow to electrode 21 of the right-hand valve 13. In order to prevent reverse current flow through the exciting electrodes 20 and 21 which receives the negative impulse, a polarity sensitive circuit is provided in shunt with the exciting electrodes 20 and 21. Preferably this polarity sensitive shunt 30 is in the form of a unidirectional conductor such as a dry rectifier.

In order to control the time instant of the application of the ionizing impulse, I prefer to provide a suitable phase shifting device 31 in series with the alternating-current source 25. I also prefer to provide a circuit interrupting device 35 in series with each of the starting electrodes 20, and energize this circuit interrupting device 35 by the current flowing to the keep-alive electrode 21. In this manner the starting electrode 20 will operate only until such time as normal current flows to the keep-alive electrode 21. At this time the flow of current to the keep-alive electrode 21 will actuate the circuit interrupter 35 and take the starting electrode 20 out of service for such period as current continues to flow to the keep-alive electrode 21. The starting electrode 20 is thus maintained normally inactive by flow of current to keep-alive electrode 21, which holds circuit interrupter 35 in open position. The starting electrode then only operates at initial starting of the valve, or restarting in the event of current interruption through keep-alive electrode 21.

It is sometimes desirable to provide a control potential to the anode shield 17. When this is desirable, a suitable shield control transformer 36 may be supplied, and preferably is connected in parallel with the alternating-current source 25, so that the shield potential will be at a maximum positive potential at the time of the ionizing impulse as shown in Cox et al., Patent 2,259,293.

In the operation of the device according to my invention, the circuits 10 and 11 will be connected to the interconnecting transformer 12 and circuit 10 will be connected to the exciting potential sources 22 and 25. A direct-current 40 will then flow to both of the starting electrodes 20 of the pair of valves 13, and at the proper interval a current impulse 41 will be delivered to one of the starting electrodes 20. This current impulse 41 will be sufficiently high to initiate a cathode spot after which the current will pickup to the

keep-alive electrode 21 and the flow of current to the keep-alive electrode 21 will open the circuit interrupting device 35 in series with the starting electrode 20. The other half-cycle from the impulsive device will likewise pickup the other or alternately conducting valve in like manner, the shunt circuit 30 around the excitation electrodes 20 and 21, preventing the flow of reverse current which otherwise would terminate the flow of current from the exciting or keep-alive electrode 21.

While I have shown and described a specific embodiment of my invention, it will be apparent that changes and modifications can be made therein without departing from the true spirit of my invention or the scope of the appended claims.

I claim as my invention:

1. An electric current translating system interconnecting a direct-current circuit and an alternating-current circuit comprising at least a pair of alternately conducting valves, each valve having a main anode and cathode in an evacuated container, a starting electrode in each valve, a keep-alive electrode in each valve, a source of alternating potential, circuit means including a saturable reactor for connecting said source of alternating-current potential to said starting electrodes and said keep-alive electrodes, a high impedance reactor connected across the output terminals of said circuit means, a source of direct current, and connections for impressing the potential of said source of direct current between the mid-point of said reactor and the cathodes of said valves.

2. An electric current translating system interconnecting a direct-current circuit and an alternating-current circuit comprising at least a pair of alternately conducting valves, each valve having a main anode and cathode in an evacuated container, a starting electrode in each valve, a keep-alive electrode in each valve, a source of alternating potential, circuit means including a saturable reactor for connecting said source of alternating-current potential to said starting electrodes and said keep-alive electrodes, a high impedance reactor connected across the output terminals of said circuit means, a source of direct current, and connections for impressing the potential of said source of direct current between the mid-point of said reactor and the cathodes of said valves, and circuit interrupting means connected in series with said starting electrodes.

3. An ignition system for a vapor-electric valve comprising a starting electrode in said valve, an exciting electrode in said valve, a source of substantially constant direct current connected to said electrodes, an auxiliary source of periodic potential connected to said electrodes, and switching means responsive to current flow to said exciting electrode to determine current flow to said starting electrode.

4. An electric current translating system for interconnecting a direct-current circuit and an alternating-current circuit comprising a pair of alternately conducting vapor-electric valves, each valve including a main anode and cathode and exciting electrodes including an electrode in contact with the cathode and an electrode spaced from the anode and cathode, a source of alternating-current potential, a circuit for connecting opposite terminals of said alternating-current source to the exciting electrodes of the respective valves, a source of direct current, a reactor con-

5

connected across the output terminals of said circuit, a tap intermediate the ends of said reactor and circuit means for impressing the potential of said source of direct current between said tap and the cathodes of said valves.

5. An electric current translating system for interconnecting a direct-current circuit and an alternating current circuit comprising a pair of alternately conducting vapor-electric valves, each valve including a main anode and cathode and exciting electrodes including an electrode in contact with the cathode and an electrode spaced from the anode and cathode, a source of alternating-current potential, a circuit for connecting opposite terminals of said alternating-current source to the exciting electrodes of the respective valves, a source of direct current, a reactor connected across the output terminals of said circuit, a tap intermediate the ends of said reactor and circuit means for impressing the potential of said source of direct current between said tap and the cathodes of said valves, circuit interrupting means in series with the electrodes in contact with the cathodes and means energized by current flow to the associated spaced electrode for actuating said circuit interrupting means.

6. An exciting system for a vapor-electric valve comprising a source of substantially constant direct current, a source of alternating current, wave distorter means for producing periodic current impulses of short duration from said alternating-current source, a starting electrode in said valve, an exciting electrode in said valve, and connections for impressing said direct current and said current impulse in parallel on said electrodes, and phase shifting means between said source of alternating current and said wave distorter means.

7. An ignition system for a vapor-electric valve comprising a keep-alive electrode in said valve, a source of direct current exciting potential, means for connecting said source of direct current to said keep-alive electrode, the potential of said source of direct current potential being sufficient to normally maintain a keep-alive arc in said valve, a source of periodic potential, a make-alive electrode in said valve, means for connecting at least said source of periodic potential to said make-alive electrode for initiating excitation in said valve and means for impressing the potential of said source of periodic potential on said keep-alive electrode for periodically re-enforcing the excitation in said valve.

8. An ignition system for a vapor-electric valve comprising an exciting electrode in said valve, a source of direct current exciting potential, means for connecting said source of direct current to

said exciting electrode, the potential of said source of direct current potential being sufficient to normally maintain a keep-alive arc in said valve, a source of periodic potential and means for impressing the potential of said source of periodic potential on said exciting electrode for periodically re-enforcing the excitation in said valve, a starting electrode in said valve and means responsive to current flow to said exciting electrode to determine the energization of said starting electrode.

9. An exciting system for a vapor-electric valve comprising a source of substantially constant direct current, a source of alternating current, wave distorter means energized from said source of alternating current for producing periodic impulses of short duration, a starting electrode in said valve, means for impressing the impulses of short duration on said starting electrode for initiating excitation in said valve, an exciting electrode in said valve, connections for impressing the potential of said source of direct current on said exciting electrode for maintaining a keep-alive arc of low intensity in said valve and means for impressing the output of said wave distorter means on said exciting electrode for periodically increasing the intensity of excitation in said valve.

10. An exciting system for a vapor electric valve comprising a source of substantially constant direct current, a source of alternating current, wave distorter means energized from said source of alternating current for producing periodic impulses of short duration, an exciting electrode in said valve, connections for impressing the potential of said source of direct current on said exciting electrode for maintaining a low degree of excitation in said valve and means for impressing the output of said wave distorter means on said exciting electrode for periodically increasing the degree of excitation in said valve, a starting electrode in said valve and switching means responsive to current flow to said exciting electrode for controlling the energization of said starting electrode.
